UNITED STATES PATENT OFFICE

HARRY L. WHEELDEN, OF BANGOR, MAINE

POLE SETTING APPARATUS AND THE LIKE

Application filed February 3, 1931. Serial No. 513,145.

This invention relates to engineering equipment and particularly to machinery for such work as is involved in the construction or maintenance of light or power lines where poles are used to carry the wires.

In this work, the position of the post or post hole is either at some little distance from the roadside or surrounded by such conditions as to make the approach of a heavy truck or tractor impossible or inconvenient or hazardous. While my machine is adapted for and adaptable to a great variety of operations, I will for the purposes of discussion deal principally with such operations as the digging of post or other holes, the erection and setting of the posts themselves, the filling and tamping of such holes, the pulling of poles previously set and various other and kindred operations including those of digging and drilling, lifting or transferring as where poles, heavy equipment, rock or other heavy materials have to be transferred from a position at one side of a roadway to another position, as for example, to another truck.

It is highly desirable in such operations that the number of pieces of equipment necessary for any job be as few as possible, but the difficulty involved is that of the varied nature of the work which has to be done and the circumstances attendant on its performance.

A large number of different pieces of special equipment is not only expensive and inconvenient to move from place to place, but the multiplication of equipment causes congestion on the job. My invention provides a means whereby all the foregoing operations may be effected simply by attaching the suitable work member or tool to my operating head.

My concept of efficiency in machinery for such operation is that of a machine of simple and yet powerful type and having a sufficient versatility to enable it to perform all of the usual operations required and to do so under most of the conditions which are encountered.

As illustrative of my invention I have shown in the accompanying drawings equipment illustrative of the principles involved and while my invention is capable of em-

bodiment in various forms and may be worked out in various detail of special requirements, the accompanying drawings afford a basis for my discussion of my invention, its general embodiments and such special features as are important for success.

In the accompanying drawings I have shown the machine as of the so-called caterpillar tractor type and for most purposes such type of self-propelled machine is preferable. I have heretofore referred to roadways, but this is to be understood as a general term meaning such ways or routes as may have to be travelled by such equipment in performing any particular piece of engineering. Such ways may, of course, in the case of light and telephone or telegraph lines be along or adjacent to a roadway or highway but on the other hand particularly in the case of transmission lines the work most often has to be pushed straight through rough and difficult country in which case the capacity of the tractor tread type for getting into and out of difficult positions is of great importance.

Throughout the specification and drawings like reference characters are employed to indicate corresponding parts, and in the drawings:

Fig. 1 is a side elevation of equipment in accordance with my invention.

Fig. 2 is a plan view of a portion thereof.

Fig. 3 is an enlarged plan view of the arms, work head and drives and adjustments.

Fig. 4 is a fragmentary detail of the bearing extension of the head.

Fig. 5 is a sectional view through one of the extensible arms on the line 5—5, Fig. 3.

Fig. 6 is a transverse section on the line 6—6, Fig. 5.

Fig. 7 is a sectional detail of the driving head and digger.

Fig. 8 is a partly sectioned detail of lifting jack attachment for the head.

Fig. 9 is a plan view of the foot thereof.

Fig. 10 is a view of the head with auxiliary hoisting pole, and

Fig. 11 is a sectional view showing the digger in enlarged section.

My equipment as herein illustrated is mounted on the frame of a truck T. Such vehicle may be of any type, but preferably is of heavy duty construction and preferably having a caterpillar rear C as affording a stable base for operation and as best adapted for negotiating soft ground or rough land.

On the rear end of the truck frame I provide a rotatably mounted platform 1 adjustable by an annular rack turned by a worm 20 on the crank 2. On the platform 1 are a set of bearings 3 in which is supported a driven shaft 4.

Overhanging the platform and extending 15 beyond the rear of the truck is a frame carrying a work head. Tubular arms 5 of this frame are provided with forked heads 6 which are pivotally supported on the shaft 4 and are each provided with a slidable 20 extension or telescopic member 7 adjustable by a pinion 8 engaging a rack 9 carried by the extension 7. The pinion 8 is operated by the crank 10 on a cross shaft 11 so that the extensions may be simultaneously operated.

The extensions 7 support at their outer ends a cross frame including a head 12 which is trunnioned between end frames on the extensions 7 so as to be tiltable. One of these frames 13 provides bearing for a drive 30 shaft 14 divided as at 14' which through the bevel gears 15 drives a cross shaft 16. The shaft 16 has a bevel gear 17 meshing with a gear 18 (see Fig. 7) which is on a rotary shank holder 19 and rotatably mounted in the head 12. The other side of the head 12 which is trunnioned in the end frame 20 carried by the other arm is provided with a gear 21. This is turned by a gear 22 on a shaft 23 within a tubular arm the same being rotated in either direction by a reversing gear system 24 and clutches 25 so that the head 12 may be tilted or rocked on its axis to position the hole digger pole holder or other device at any desired angle or to manipulate 45 the same or other heavy tool or device performing the work.

The power shaft 14 is driven by a set of reversing gears 30 controlled by clutches 31, both of said drives obtaining power from the 50 cross shaft 4 which is rotated by a sprocket drive 26 and chain 27 driven from the shaft 40 which in turn is driven from any suitable source of power as a motor, indicated at P and mounted on the platform 1.

On the shaft 40 is a drum 41 on which is wound a cable 42 which passes over a sheave 43 at the top of an upright 44. This cable 42 is connected as at 45 to the head 12 and serves to raise and lower the arms and head.

On the shaft 4 is another drum 50 on which is wound a cable 51 which passes over a sheave 52 on the head 12 and is connected at 53 to the guide 54 which is slidably mounted in the head 12 and which has a hooked lower 65 end 55 engaging the hub 56 of the digger.

The drum 50 is provided with a clutch 57 and the run of the cable 51 held by a foot brake 58 with auxiliary pawl 59.

The digger comprises a stem 60 splined for slidable movement through the rotary sleeve 19 and head 12. At its lower end it is provided with a bit 61 keyed as at 66 in the shaft 60 and for slight movement relative thereto (see Fig. 7). The retreat of the bit 61 is opposed by the spring 63 contained within the stem. The digger shell 64 is mounted on the base of the hub 56 and is provided with internal spiral flanges 65 (see Fig. 1) which cut a core of earth or other material which is to be removed in forming the post 80 hole.

In operating the equipment, the vehicle is backed up in position as near to the spot as possible, and the platform 1 swung to bring the arms 5 into position. By running out the 85 extensions 7 the head 12 is brought in proper relation to the spot where the work is to be made. It will be noted that due to irregularities in the land the angle adjustment of the head 12 becomes very important and especially so in combination with the other adjustments and movements of the parts. In fact, in manipulating so cumbersome a piece of equipment, it is extremely important that the head be capable of a wide range of manipulation.

The head 12 may be angularly adjusted during any of these movements or may be secured in any angular position with respect to the tubular arms 5 by tightening the clamping screws 85 in the split hubs 86.

Aside from the hole digging, there is in any construction work the pole handling, setting, filling and tamping work to be done. In repair or maintenance work poles have to 105 be removed for re-location or butts or stumps pulled, all requiring much power, which may be supplied through my extensible arms.

As shown in Fig. 8, the head 12 is preferably provided with an extension casing 70 110 detachably mounted as by fastenings 71. This member is an auxiliary jack member for heavy pulling or lifting. On many occasions it is necessary to apply a pull or lift beyond the capacity of the hoist cable 42. To meet 115 such situations I contemplate auxiliary bases of ground contact to relieve the strain on the hoists and on the apparatus in general.

The casing 70 has a nut member 72 provided with a gear 73 which can be meshed with the gear 74 on the lower end of the driving sleeve 19. The nut 72 operates a threaded jack stem 75 provided with a foot 76. This foot is notched as at 77 to permit it to span a pole or like object to be pulled. The attachment 70 has an apertured chain connection 78 for making the hitch to the object to be lifted.

This may be used with a gin pole 80 but in such case I preferably use a simple eyed at- 130

tachment 81 having an apertured bracket 82 which will sustain the gin pole when it is used for auxiliary hoisting as where the lift cable 51 is run over its block 83. Such a gin pole is preferably provided with a pivoted foot 84 to give proper bearing on uneven ground or permit angular erection.

Apparatus in accordance with my invention may be used to perform or assist in the performance of a great variety of general operations as well as those specifically referred to. The extensible and swinging arms make a convenient hoist for handling heavy tools or other equipment or materials. The tiltable head is particularly adapted for elevating and setting the poles or for removing poles previously set. The hoists either singly or in combination or working with the truck as a movable factor provide a piece of equipment of great utility and one capable of being operated under all reasonable service conditions.

What I therefore claim and desire to secure by Letters Patent is:—

1. In an apparatus of the class described, a vehicle, a horizontally disposed platform rotatably mounted thereon, a pair of extensible spaced arms pivoted to said rotatable platform and having a head between their free ends, an upright on said platform, a reversible hoist, a flexible connection wound on said hoist and passing over said upright for raising and lowering the arms, and means for rotatably adjusting the platform on its vertical axis.

2. In an apparatus of the class described, comprising a support, a horizontally disposed platform rotatably mounted thereon, a pair of spaced extensible arms pivoted to said rotatable platform and having a head between their free ends, a rotatable member in said head, a drive for the rotatable member in said head, a jack member carried by said head including a nut, a screw and means for driving the nut from the rotatable head member.

3. In an apparatus of the class described, comprising a support, a horizontally disposed platform rotatably mounted thereon, a pair of spaced extensible arms pivoted to said rotatable platform and having a head between their free ends, a rotatable member in said head, a drive for the rotatable member in said head, said head being tiltably mounted between said arms on the axis of said driving connection, a jack member carried by said head including a nut, a screw and means for driving the nut from the rotatable head members.

4. In an apparatus of the class described, comprising a support, a horizontally disposed platform rotatably mounted thereon, a pair of spaced extensible arms pivoted to said rotatable platform and having a head between their free ends, a rotatable member in

said head, a drive for the rotatable member in said head, said head being tiltably mounted between said arms on the axis of said driving connection, a reversible hoist for the arm, a jack member carried by said head including a nut, a screw and means for driving the nut from the rotatable head member.

5. In an apparatus of the class described, comprising a support, a horizontally disposed platform rotatably mounted thereon, a pair of spaced extensible arms pivoted to said rotatable platform and having a head between their free ends, a rotatable member in said head, a drive for the rotatable member in said head, said head being tiltably mounted between said arms on the axis of said driving connection, a reversible hoist for the arms, a jack member detachably carried by said head including a nut, a screw and means for driving the nut from the rotatable head member, and disconnectible therefrom.

6. In an apparatus of the class described, a support, a pair of spaced extensible arms pivotally mounted on said support, a head casing trunnioned between the arm ends, a member rotatably mounted therein, a drive for reversibly rotating the member, a jacking attachment for the head including a nut and a screw, and means connectible with the head drive when the attachment is in place so as to be operated by the head drive.

7. In an apparatus of the class described, a support, an extensible arm pivotally mounted on said support, a head casing carried at the arm end, a member rotatably mounted therein, means for reversibly rotating the member, a gear on said member, a jack casing, means for detachably mounting it on the head, a nut and a screw in the jack casing, a gear on the nut and intermeshable with that of the head when the attachment is in place so as to be operated by the head gear.

8. In an apparatus of the class described, a vehicle, a horizontally disposed platform mounted thereon on a vertical bearing, a pair of spaced telescopic arms pivoted to said rotatable platform, a head between the free arm ends, means for raising and lowering the head and arms.

9. In an apparatus of the class described, a vehicle, a horizontally disposed platform mounted thereon on a vertical bearing, a pair of spaced telescopic arms pivoted to said rotatable platform, a head between the free arm ends, said head being tiltably mounted between said arms on the axis of said driving connection, a head adjusting shaft on the other of said arms and operatively connected to said head to tilt it on its axis, and means for reversibly driving the head adjusting means, means for raising and lowering the head and arms.

10. In an apparatus of the class described comprising a vehicle, an extensible arm pivotally supported thereon, an angularly adjust-

- able head on the arm and a rotatable driving member in said head, a driven member carried by said head, and means for vertically adjusting and laterally swinging said arm.
5. 11. In an apparatus of the class described comprising a vehicle, a horizontally disposed platform rotatably mounted thereon, an extensible arm pivotally mounted on said platform, an angularly adjustable head on said 10 arm, a rotatable driving member in said head, a driven member carried by said head, means for adjusting said arm vertically, means for rotatably adjusting the platform, and means for operating said driven member.
15. 12. In an apparatus of the class described comprising a support, an extensible arm pivotally mounted on said support, an angularly adjustable head on said arm and a rotatable driving member in said head, a driven 20 member carried by said head and operatively connected thereto, and means for vertically adjusting the arm and laterally swinging the arm.
25. 13. In apparatus of the class described comprising a vehicle, a horizontally rotatable platform mounted thereon, an extensible arm pivotally mounted on said platform, an angularly adjustable head on said arm, a rotatable driving member in said head, a 30 driven member carried by said head and connected to said driving member, and means for operating said driving member in said head.
35. 14. In apparatus of the class described, a pair of spaced extensible arms pivotable to said rotatable support and having a head between their free ends, a rotatable member in said head, a drive for the 40 rotatable member, means for adjustably tilting the head on its axis, a reversible hoist for raising and lowering the head and arms, a driven member carried by said head member and means for operating said driven member.
45. 15. In an apparatus of the class described, a vehicle, a horizontally disposed platform mounted thereon, a pair of spaced telescopic arms pivotable to said rotatable platform, a head between the free arm ends, a rotatable member in said head, a drive shaft extending through one of said arms and operatively 50 geared to the rotating member in said head, said head being tiltably mounted between said arms on the axis of said driving connection, a reversible drive for said drive shaft, a head adjusting shaft on the other of said 55 arms and operatively connected to said head to tilt it on its axis, means for reversibly driving the head adjusting means, means for raising and lowering the head and arms, a driven member carried by said head and 60 means connecting said driven member to said rotatable member in said head.
65. 16. In an apparatus of the class described comprising a support, a horizontally disposed platform rotatably mounted thereon, a pair of spaced extensible arms pivotable to said

rotatable platform and having a head between their free ends, a rotatable member in said head, a drive for the rotatable member in said head and a driven member carried by said head and means for driving said driven member from the rotatable head member. 70

17. In an apparatus of the class described comprising a support, a horizontally disposed platform rotatably mounted thereon, a pair of spaced extensible arms pivoted to said rotatable platform and having a head between their free ends, a rotatable member in said head, said head being tiltably mounted between said arms on the axis of said driving connection, a driven member carried by said head and means for driving said driven member from the rotatable head member. 75

18. In an apparatus of the class described, a support, a pair of spaced extensible arms pivotally mounted on said support, a head casing trunnioned between the arm ends, a member rotatably mounted therein, a drive for reversibly rotating the member, a driven member mounted on said head and means connectible with the drive for said head member so as to be operated thereby and to operate said driven member. 80

19. In an apparatus of the class described, a pair of spaced extensible arms pivotally mounted on said support, a head pivoted between the free ends of said arms, a rotatable driving member in said head and a suitable driven member supported by said head. 85

In testimony whereof I affix my signature. 90
